UNITED STATES PATENT OFFICE.

FRANK L. O. WADSWORTH, OF SEWICKLEY, PENNSYLVANIA.

WATER-HEATER CONSTRUCTION.

1,156,949.

Specification of Letters Patent.

Patented Oct. 19, 1915.

Application filed December 26, 1911. Serial No. 667,947.

To all whom it may concern:

Be it known that I, FRANK L. O. WADSWORTH, a citizen of the United States, residing at Sewickley, in the county of Allegheny and State of Pennsylvania, have invented 5 certain new and useful Improvements in Water-Heater Construction, of which the following is a specification.

The invention relates to improvements in 10 water heater construction, and particularly to the automatic controlling mechanism for governing the supply of gas to the burners. The invention has for its object; the provision of improved combined water pressure and thermostatic controlling means for governing the supply of gas to the burners. Certain embodiments of the invention are 15 illustrated in the accompanying drawings, wherein:—

Figures 1 and 2 are front and side elevations respectively of the ordinary modern instantaneous heater, such as that shown in the patent to Shook, Number 993,723, with my improvement applied thereto; Fig. 3 is 20 a transverse section on an enlarged scale through my controlling mechanism; and Fig. 4 is a section through a modified form of the invention.

Referring first to the general arrangement 25 of the heater parts as shown in Figs. 1 and 2, A is the casing of the heater; B and C are the upper coils of the heater; D is a lower reverse coil connected to the upper coils by means of the pipe E; F are the 30 burners mounted upon the usual burner ring; G is the gas supply pipe; H is the casing of the gas valve for controlling the supply of the gas to the burners; I is a pipe leading from the gas valve to the burner 35 ring; and K is the casing of the water valve. The details and construction of the controlling mechanism which constitutes my invention will now be described, it being understood that such controlling mechanism is of 40 general application and not limited to use upon the particular type of heaters shown in Figs. 1 and 2.

Referring now to Fig. 3 in connections 45 with Figures 1 and 2; 1 is the cold water pipe leading from the main, which pipe is provided with a T 2, one side of which is connected with the chamber 3 in the casing K and the other side of which is connected to the pipe 4, such pipe 4 connecting at its 50 upper end by means of the connection 4' (Fig. 2) with the upper coil B of the heater.

The lower coil D of the heater has its outlet end 5 connected to the lower end of the thermostat casing 6, the pipe 6' (Fig. 2) leading from the upper end of such thermostat chamber 6 being the outlet leading to the house service pipes. The chamber 3 and the thermostat chamber 6 are connected respectively, by the passages 7 and 8 to the opposite ends of a cylinder 9 in which is located the fluid pressure actuated piston member 10. This member is connected by the stem 11, passing through a stuffing box 12, to a link 13 pivoted on the end of the stem 14, of the gas valve 15. The piston member 10 is preferably of the packing ring construction, and is held normally in position at the left hand end of the cylinder 9 by the unbalanced pressure of the water in the cylinder against the head of the stem 11, this pressure being supplemented, if desired, by a spring 16. Located in the thermostat chamber 6 is a double acting thermostat of the usual construction having an outer positive member 17 and an inner negative member 18, the positive member 17 being secured in position at the lower end of the thermostat chamber and the inner negative member being secured at its upper end to the positive member 17, and bearing at its lower end on the short arm of the thermostat lever 19. The long arm of this latter lever engages with a collar 20 mounted on a stem 21 which passes through a stuffing box in the right hand end of the cylinder 9. The stem 21 is threaded to receive a screw 22 which screw extends clear through the stem and constitutes an adjustable means for engaging the head of the stem 11. The collar 20 is kept in engagement with the thermostat lever by a strong compression spring 23. The gas valve 15 is of large diameter so that a very slight longitudinal movement away from its seat will open the gas valve port to the full capacity of the fuel supply and discharge pipes G and I. I also avoid the necessity of using a packing box around the stem of this valve by locating the head 15 so close to the end of the valve box chamber that the withdrawal of said valve from its seat brings the washer 26 into direct contact with the head of the valve box chamber and thereby seals the opening around the stem against escape of any gas. The head of the piston 10 is similarly provided with a washer 26' which seals the opening around the stem 11 when the parts are in the closed position.

The gas valve box containing the gas valve 15 is also fitted with an ordinary plug valve 27, and a connection 28 leading to the ordinary pilot light which is provided for the ignition of the gas supplied to the main burners through the pipe 1.

The operation of the above described apparatus is as follows: When no water is flowing through the heater and the temperature in the thermostat chamber 6 is lower than that at which the thermostat may be set to act, the pressures at the inlet and outlet points, and in the chambers at the two ends of a cylinder 9 are the same, and the gas valve 15 is held closed by the pressure of the water on the stem 11. When the water begins to flow through the heater, a difference in pressure will be set up at the inlet and outlet by reason of the resistance 10 to the passage of the liquid through the heater chamber or coils, and this difference of pressure being communicated through the passages 7 and 8 to the liquid on the two sides of the piston 10, the latter will—if the 15 temperature of the out flowing water is less than that for which the thermostat is set to act—be moved to the right carrying with it the stem 11 and link 18, thereby opening the gas valve 15 and admitting fuel to the 20 main burners of the heater. When the flow of water is stopped the pressures in the two ends of the cylinders 9 will again equalize themselves, and the fluid actuated piston member 10 will return to its normal left 25 hand position, allowing the fuel valve 15 to close. If while the water is still flowing the temperature in the thermostat chamber 6 rises above a certain point, the expansion of 30 the positive element 17 of the thermostat 35 will allow the thermostat lever 19 to move sufficiently to the left to bring the end of the screw 22 into contact with the head of the stem 11, and a further rise of temperature will allow the latter to be forced back 40 to its normal left hand position by the pressure of the spring 23, the latter being of sufficient strength to overcome the differential pressure set up by the flow of the water on the opposing sides of the cylinder 9. 45

50 When the temperature falls the contraction of the thermostat element 17 will move the thermostat lever 19 to the right, thus compressing the spring 23 and withdrawing the screw 22 from engagement with the head of the stem 11 and will allow the fluid pressure actuated piston member 10 to again open the gas valve 15.

In the construction shown in Fig. 4, 1² is (as before) a cold water supply pipe leading from the water main. This pipe enters a cored chamber 3² which passes around one side of a diaphragm chamber 30, as indicated in the dotted lines and communicates with the interior of the latter through a port 66 7². At the upper opening of the chamber

3² there is placed a spring check valve 31 and from the opening above this check valve a pipe 4² leads to the cold water inlet of the heater coils. This space is also in communication through a port 32 with the right hand 70 side of the diaphragm chamber 30. The fluid actuated pressure member consists in this case of a diaphragm 33 clamped at its outer edge between two parts of the diaphragm chamber 30, and connected at its 75 center with a stem 34 leading through a stuffing box and coupled at its outer end to a U shaped link 35 which engages in turn with the lever 36. The short end of this lever 36 is pivoted on a stationary knife 80 edge 37 on the head of the diaphragm chamber, and the long end is connected to the stem 14² of the gas valve 15² which is similar in its construction to that shown in Fig. 1. The stem 14² and the gas valve 15² are in 85 this case held in their closed position by a spring 40, and this same spring serves also to hold the lever 36 in operative engagement with the parts 35 and 37. The stem 34 is made hollow to receive an adjusting screw 90 41 which is threaded at its inner end through the central cap on the diaphragm 33. The water after passing through the heater chamber or coils emerges at the outlet 5², enters a thermostat chamber 6² which is 95 formed in the right hand end of the diaphragm chamber 30, and then enters the pipe 6³ which connects with the house supply system. The thermostat chamber 6² is bored to receive the liquid thermostat element 45, this thermostat element being constructed in the form of a corrugated box or cylinder with sides of thin sheet metal and with ends of heavy plates one of which 46 forms a packed piston head separating the 100 right hand end of the diaphragm chamber 30 from the thermostat chamber 43, and the other of which constitutes a screw cap closing the other end of said thermostat chamber. The corrugated box 45 is filled with 105 some liquid having a high thermal coefficient of expansion, such as ether, or alcohol, or crude petroleum, and is hermetically sealed.

The operation of this form of apparatus is the same as of that shown in Fig. 1, the 115 only difference being that when water is flowing through the heater, the differences of pressures which are set up on two sides of the fluid actuated member 33 are produced by the action of the check valve 31. As soon as the temperature is less than that for which the thermostat is set to act, the movement of the gas valve 15 will be controlled entirely by the water pressures on the two sides of the diaphragm 33; but when the temperature rises above a certain point the expansion of the liquid in the thermostat box 45 will force the head 46 far enough to the left to either restore the diaphragm 33 to its initial position (thereby closing 120 125 130

the gas valve, if it is open), or to prevent said diaphragm from leaving its initial position until the temperature falls again. Since the movement of the gas valve is many times greater than the movement of the diaphragm 33 and stem 34, a very small movement of the head 46 of the thermostat is sufficient to control the said movements and effect a close temperature regulation of the out-flowing liquid.

In the construction shown in both of the above figures, the action of the thermostat in closing the gas valve 15 involves the return of the fluid actuated member to its initial position against the differential pressure set up on the two sides of that member by the flow of the water through the heater. There is no difficulty however, in making a thermostat having sufficient power to do this, as the area of the fluid pressure actuated member may be made quite small, and said member has to be moved, not against the fluid pressure of the water in the heater, but only against the differential pressure on its two sides.

Having thus described my invention and illustrated its use, what I claim as new and desire to secure by Letters Patent is the following:

1. In an automatic water heater, a burner, a gas valve for controlling the supply of gas to the burner, a pair of pressure chambers connected to portions of the heater having different water pressure when the outlet from the heater is open, a member actuated by the differential pressures in the chambers for opening the gas valve, and a thermostatic means governed by the heated water and arranged so as to move the said member back toward the position at which the gas valve is closed in case the temperature of the water in the heater rises above a predetermined point, the parts being arranged so that a yielding closure of the gas valve is secured under all conditions and so that the thermostat means may continue in its closing movement after the gas valve is closed.

2. In an automatic water heater, a burner,

a gas valve for controlling the supply of gas to the burner, a pair of pressure chambers connected to portions of the heater having different water pressure when the outlet from the heater is open, a member actuated by the differential pressures in the chambers and arranged so as to pull the gas valve open when the differential pressure is applied to the member, and a thermostatic means governed by the heated water and arranged so as to force the said member back to normal position and cause the closure of the gas valve when the temperature of the water in the heater rises above a predetermined point, there being a lost motion connection between the thermostatic means and the gas valve whereby the thermostatic means may continue its valve closing movement after the gas valve is closed, without imposing additional strain thereon.

3. In an automatic water heater, a conduit through which the water passes to be heated, a burner, a gas valve for controlling the supply of gas to the burner, a pair of pressure chambers lying outside the conduit but connected to portions of the conduit having different water pressure when the outlet from the heater is open, means actuated by the differential pressures in the chambers for opening the gas valve, and a thermostatic means mounted independently of the said member and arranged with a space between the parts of the said water actuated means and the thermostatic means when the outlet from the heater is closed and the water below a predetermined temperature but governed by the heated water and arranged so as to move the said water actuated means back toward the position at which the gas valve is closed in case the temperature of the water in the heater rises above a predetermined point.

In testimony whereof I have hereunto signed my name in the presence of the two subscribed witnesses.
